UNITED STATES PATENT OFFICE.

CHESTER E. WARNER, OF BERWYN, ILLINOIS, ASSIGNOR TO BENJAMIN ELECTRIC MANUFACTURING COMPANY, OF CHICAGO, ILLINOIS, A CORPORATION OF ILLINOIS.

PLURAL PLUG.

Application filed June 29, 1922. Serial No. 571,659.

My invention relates to electrical connector devices and more particularly to molded two-way plugs. In a two-way plug it is desirable that the longitudinal axis of at least 5 one of the receptacles should be in parallel relation to the axis of the plug so that the lamp may stand in substantially the same relative position with regard to the fixture socket or receptacle that it does when used 10 without the two-way plug. It is also desirable that the shell contacts should be molded into the insulating base of the plug before any of the electrical connections are secured thereto. This has been difficult to do in the 15 past on account of the difficulty of making the electrical connections after the shell contacts were molded into the base.

Another objection to the ordinary two-way plug of this type has been that no provision has been made for moving the angular 20 receptacle to any desired position around the axial line of the plug after the plug has been screwed into a socket.

In my invention I have successfully overcome 25 these difficulties and it has for one of its objects to provide a plural plug having the receptacle shell contacts molded into a unitary mass of insulating material and in which the axis of one of the receptacles is in 30 substantially parallel relation to the axis of the plug portion.

Another object of my invention is to provide a two-way plug having receptacle contacts molded into a unitary mass of insulating 35 material and having the axial line of one of the receptacles in substantially parallel relation with the plug portion and the axial line of the other receptacle in angular relation to the axes of both the plug portion and 40 the parallel receptacle.

Another object of my invention is to provide a swivel two-way plug in which the receptacle contacts are molded into a unitary mass of insulating material having the 45 plug portion and one of the receptacle contacts in parallel relation and in which the angularly disposed receptacle portion may be adjustably rotated around the axis of the plug portion.

Another object of my invention is to provide 50 an improved two-way plug of few parts which will be durable and efficient in use, simple in construction, cheap to manufacture and easy to assemble.

A further object of my invention is to 55 provide improved means for assembling a two-way plug in which the shell receptacle contacts are molded into an insulating housing and positioning member.

Further objects will appear from the detailed description to follow and from the appended claim.

In the drawings in which an embodiment of my invention is shown:

Figure 1 is a side elevation of my improved plug embodying my invention;

Fig. 2 is a bottom view of the two-way plug as illustrated in Fig. 1;

Fig. 3 is a vertical longitudinal section taken on line 3—3 of Fig. 4;

Fig. 4 is a vertical longitudinal section taken on line 4—4 of Fig. 3;

Fig. 5 is a transverse sectional view taken on line 5—5 of Fig. 4;

Fig. 6 is a plan view of the spring washer 75 for providing frictional and electrical contact between the base portion and the swivel shell;

Fig. 7 is a perspective view of the shell connector;

Fig. 8 is a vertical longitudinal section of the base showing the threaded shell contacts molded in; and

Fig. 9 is a top view of the base portion as shown in Fig. 8;

Referring now to the drawings in detail, in my invention as illustrated, I provide a base portion 10 and a plug portion 11, the base portion comprising a unitary mass of insulating material forming a housing and positioning member for the threaded shell contacts 12 and 13 which are molded therein, the axis of the threaded shell contact 12 being in substantially parallel relation to the axis of the plug portion 11 and slightly offset therefrom, and the side receptacle shell contact 13 being angularly disposed with relation to the axis of the plug portion and the receptacle shell contact 12. The receptacles are provided with suitable center contacts 14 and 15.

The plug portion 11 comprises a plug base 16 having a swivel shell contact 17 mounted thereon. The plug portion is also provided with a center contact 18 which in the construction shown is the head of the screw 19 which extends through the axial opening 20 in the plug base 16. The receptacle center

contact screws 14 and 15 extend through the openings 21 and 22 respectively, and are threaded into the supporting member 23, the supporting member being arranged to rest on the shoulder 24 in the base 10, the portion 25 of the supporting member being turned upwardly to receive the receptacle center contact screw 15. The plug center contact screw 19 is also screwed into the supporting member 23, thus securing all of the parts in operative relation.

The receptacle shell contact 12 is provided with an upwardly extending portion 26 which is sheared out of the end of the receptacle shell contact 12 after the insulating base has been molded, as shown in Fig. 8, and is bent upwardly and into contact with the receptacle shell contact 13, as illustrated in Fig. 3.

The connector 27 is inserted in the opening 28 and is clamped against the upwardly extending lug 26 by means of the screw 29 extending through the threaded shell contact 13, thus securing the threaded shell contact 13 and the threaded shell contact 12 and the connector 27 securely in electrical contact. The threaded shell contact 13 is drilled to receive the screw 29 after the shells are molded in the insulating base. The connector 27 extends upwardly and to one side of the supporting member 23 and is formed at 30 to receive the screw 31, which is arranged to clamp the spring friction washer 32 securely against the upper end of the base 10. The washer 32 is provided with the depressed portion 33 arranged to engage a lug 34 in the base 10 to prevent relative movement between the parts.

The threaded shell plug contact 17 is secured to an insulating ring 35 and is provided with a shoulder 36 arranged in frictional engagement with the plug base 16. The threaded shell plug contact 17 is also provided with an outwardly turned portion 37 arranged to engage the spring friction washer 32, thus providing an electrical connection through the threaded shell plug contact, through the spring washer 32, the screw 31, the connector 27 and by means of the clamping screw 29, through the threaded

shell contacts 12 and 13. It will also be noted that all of the center contacts are electrically connected by means of the supporting member 23.

The plug base 16 is prevented from rotating with relation to the base 10 by means of the lugs 38 on the spring washer 32 extending into the openings 39 therein.

When the center contact screw 19 is screwed into the connector 23, all the parts are held securely in assembled relation. The screw 19 is tightened sufficiently to hold all of the parts rigidly in fixed relation to each other while the plug portion is being screwed into a receptacle, a further pressure on the base 10 will allow it to be turned, thereby enabling the user to place the angular threaded shell receptacle 13 in any desired position.

The inner ends of the receptacle shells are substantially frusto-conical as illustrated thereby allowing the device to be made considerably smaller than would otherwise be the case.

A standard shade holder thread 40 is molded in the base portion 10 as illustrated, and arranged to receive a standard shade holder, the molded bead 41 providing a stop for the shade holder.

While I have shown but one form of my invention it is obvious that it may be embodied in other forms as covered and defined by the appended claim.

Having thus fully described my invention I claim as new and desire to secure by Letters Patent:

A base for a two-way plug comprising an insulating housing and positioning member having a pair of threaded shell receptacle contacts molded therein, the ends of said threaded shell receptacle contacts being substantially frusto-conical shaped, the side of the frusto-conical shaped portion of one of said threaded shell receptacle contacts being in substantially parallel relation with the axis of the other threaded shell receptacle contact.

In witness whereof, I have hereunto subscribed my name.

CHESTER E. WARNER.
